FIG.

UNITED STATES PATENT OFFICE

2,048,157

RAILROAD HIGHWAY CROSSING

Charles L. George, Findlay, Ohio, assignor to The Buckeye Traction Ditcher Company, Findlay, Ohio, a corporation of Ohio

Application May 27, 1935, Serial No. 23,557

6 Claims. (Cl. 238—9)

This invention relates to railroad highway crossings, and particularly to removable filler means for the spaces customarily left in the pavements of such crossings at the sides of railway rails to form a comparatively smooth crossing surface and at the same time permit access to the rail.

The object of the invention is the provision of a filler means of this character, which is composed of few parts, is strong and durable in its construction, is simple and inexpensive to install and is capable of easy and quick removal to facilitate access to a rail for inspection, repair or replacement.

Other objects and advantages of the invention will be apparent from the following detailed description thereof, and from the accompanying drawing, in which—

Figure 1 is the plan view of a crossing embodying the invention with parts broken away; Fig. 2 is an enlarged section on the line 2—2 in Fig. 1; Fig. 3 is an enlarged section on the line 3—3 in Fig. 1; Fig. 4 is an enlarged section on the line 4—4 in Fig. 3; Fig. 5 is a sectional detail illustrating a slightly modified form of attaching the tread plates to the supports, the section being taken on the line 5—5 in Fig. 6, and Fig. 6 is a section thereof taken on the line 6—6 in Fig. 5.

Referring to the drawing, 1—1 designate the rails of a railway track and 2 the permanent paving construction at opposite sides of each rail at a crossing with its top surface substantially level with the rail tops. A free space 3 is provided between each side of a rail and the paving material 2 to render access to a rail to permit inspection, repair or replacement thereof, and the edges of such material which form the sides of the spaces opposed to an associated rail are preferably faced with metal plates or strips 4. These plates extend upward from the ties 5 to the top surface of the paving material, are anchored to the material in any suitable manner and have their exposed sides substantially smooth.

The filler means embodying the invention is mounted in each space 3 and is coextensive in length with the width of the crossing. Such means includes a plurality of supports 6 mounted on the ties in suitably spaced relation lengthwise of the respective space 3, and one or more tread plates 7 mounted end to end on the supports 6, if more than one plate is used, and in width extending substantially from the top edge of the associated material facing plate 4 to the adjacent side of the rail.

Each support 6 is substantially I-form in cross-

section to provide a base 8 for seating on a tie at a side of the rail base, an upstanding web 9 which is transverse to the rail, and a top 10. The edge of the web 9 opposed to the rail is oppositely flanged as at 11 a distance up from its base 5 to provide a broad side surface for abutment against the plate 4. The base 8 is apertured at opposite sides of the web to receive screws, spikes, or other means for attaching the supports to the ties. The support top 10 has its inner and outer 10 edges, relative to the rail, turned down, with the outer edge spaced from the plate 4 to permit the insertion of a down-turned edge of the tread plate therebetween. The top 10 is also preferably of greater width, transverse to the rail, than 15 the base 8 to permit its inner edge to lie relatively close to the side of the rail head, while the base 8 is suitably spaced from the rail base to prevent interference with the tie plate 12. The web 9 is also accordingly broadened at its top 20 portion and its inner edge is oppositely flanged, as at 13.

The top 10, substantially midway between its inner and outer edges, forms a depression or groove 14 which extends from edge to edge thereof parallel to the rail. A bolt receiving aperture 15 is provided in the bottom of this groove in vertical register with the web 9 and with an opening 16 in the top portion of said web.

Each tread plate 7 is preferably composed of 30 rolled stock and may be of any suitable length for one or more, placed end to end, to extend from one end to the other of the space 3 in which disposed. This plate has its outer edge turned down to provide an edge flange 17 for insertion 35 into the space between the outer edge of a support top 10 and the plate 4, and its inner edge portion is dipped down, as shown at 18, and then continues horizontally or in a plane parallel to the major top portion of the plate to form a lip 40 19 for extending under the adjacent side edge of the rail head. This lip is provided with an edge notch 20 where necessary to fit around a fishplate 21. The flange portions 17 and 18 are suitably spaced to receive the support top 10 45 therebetween and to center the plate thereon. The body portion of the plate 7 is formed intermediate its side edges and throughout its length with a depression 22 for seating in the support groove 14 and to provide a bolt head receiving 50 groove 23.

The plate 7 is secured to the several supports 6, on which it is mounted, by bolts 24 inserted through apertures in the bottom of the groove 23 in register with the apertures 15 in the respective 55

supports, and threaded into nuts 26 disposed in the web openings 16. The nuts are held against turning by fitting up into complementary recesses 27 in the under sides of the support tops 10. The openings 16 are sufficiently deep to permit the nuts to be inserted sidewise therein and then placed in the recesses 27 where they are held by key members 28 of pliant material, which are inserted through the bottom of the openings 16 beneath the bolt and which then has its end portions bent down at opposite sides of the web 9 to prevent accidental removal from the openings.

It is apparent that the heads of the bolts 24 are disposed in unobstructing position within the plate grooves 23; that the plates are shaped to substantially fit the top contour of the supports 6, and that the lip edges of the plates are depressed sufficiently with respect to the rail tops as not to interfere with the flanges of wheels traveling on the rails and to project under the adjacent edge portions of the rail heads. The outer ends of the end plates of a set may be turned down, as shown in Fig. 3.

In the modification shown in Figs. 5 and 6, the bolts 24 for securing the tread plates 7 to the supports 6 are eliminated and instead the supports designated 6' are provided in their top grooves with upstanding lugs 30 which project through openings 31 in the grooved portion of the tread plate 7' and have apertures 32 through which a key 33 is inserted. The key is of soft pliant material to permit a bending of its ends at the opposite sides of the lugs 30 to prevent withdrawal. This locking means is of shallow form and does not project above the surface of the plates 7'.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. A filler means of the class described, including a plurality of supports mounted at a side of a rail in spaced relation thereto, and a tread plate mounted on the supports lengthwise of the rail at a side thereof, the supports having lengthwise extending surface grooves and the plate having a longitudinally disposed protuberant portion fitting into said grooves and forming a surface groove in the plate, said plate also having a depressed lip portion adjacent to the rail, and means disposed partially at least in said plate groove and detachably connecting the plate and supports.

2. In a device of the class described, a tread plate having a longitudinally grooved body portion with an aperture in the bottom of the groove, a support for said plate having a base, a top and an interposed vertical web, the top having an aperture therein in register with the plate aperture and with said web and the web having an opening in its top portion in register with said apertures, a bolt projecting through said apertures for detachably connecting said plate and

support and having a nut disposed in said web opening and a key removably disposed in said opening coacting with the nut to prevent its removal from the opening.

3. In a device of the class described, a tread plate having a longitudinally extending surface groove with openings through the grooved bottom, a support for the plate having a top portion fitting against the under side of the plate and having an apertured stud projecting through said openings and disposed in said groove, and a key for insertion through said stud over the grooved bottom to detachably retain the plate and support in connected relation.

4. In a device of the class described, the combination in a railroad highway crossing, of a rail, a paving material spaced from a side of said rail and having its top surface in substantially the plane of the rail top, a plurality of supports in such space having flat top portions each with a longitudinal surface groove therein parallel to the rail, a tread plate having a body portion mounted on said supports and provided with a longitudinally extending protuberant part projecting in the support grooves and forming a top groove in the plate, said body portion having an outer depending edge in substantial side abutment with the upper edge portion of the paving structure and having a downwardly extending inner edge portion forming a horizontally disposed lip which terminates adjacent to the head portion of the rail below its top, and means for detachably connecting the grooved portions of the plate and supports together.

5. In combination with a railway rail, spaced from the adjacent paving which latter has its upper surface in substantially the plane of the top of the rail, a traction plate disposed in said space having a free side lying adjacent to one side of the rail and having a second free side lying adjacent to the adjacent side of the paving, and having a shallow, narrow depression between its sides, a support for the plate, and fastening means for securing the plate to the support disposed in part in the depression to enable removal of the fastening means, and thereby the plate so as to enable access to the rail, said part of said fastening means being substantially the size of the width of the depression.

6. In combination with a railway rail spaced a relatively narrow distance from the adjacent paving, which latter has its upper surface in substantially the plane of the top of the rail, a correspondingly relatively narrow traction plate disposed in said space having its inner side depressed and lying adjacent a side of and below the top of the rail to accommodate the flange of the wheel of a railway car and having an outer portion which is turned downwardly and which lies adjacent to the adjacent side of the paving, said plate having a shallow, narrow depression intermediate the sides of the plate, supporting means for the plate, and fastening means for removably securing the plate to the supporting means disposed in part in the intermediate depression.

CHARLES L. GEORGE.
